UNITED STATES PATENT OFFICE

ROBERT F. RINGLE, OF ZELIENOPLE, PENNSYLVANIA

MOLDING MACHINE

Application filed May 29, 1929. Serial No. 366,864.

My invention refers to improvements in molding machines of the general type illustrated in prior patent of Austin and Ringle No. 1,243,030, of October 16, 1917. It has in view to provide means for making operative engagement between the raising and lowering equalizing table and the flask for accurate engagement therebetween and for lowering the flask from the pattern after molding, and reversal of the flask.

The invention specifically relates to the construction of the equalizing table whereby any inequalities or variations in parallelism between the co-operating parts may be compensated for so as to effect lowering of the flask evenly and directly away from the suspended pattern, avoiding any disturbance of the molded sand during such removal and leaving the pattern suspended from the supporting turnover plate.

The complete molding machine and the present improvement are embodied in an entire operative mechanism including the jarring table on which the flask and its contained sand are vibrated or agitated, turnover mechanism by which the flask and the packed sand surrounding the pattern are elevated away from the jarring table and rotated one-half revolution for location above the lowering mechanism, and such lowering mechanism and equalizing table, the latter forming the subject matter of the present invention.

In the drawings, illustrating one preferred embodiment of the invention:

Fig. 1 is a general view in elevation, partly in section and partly broken away, showing the several main elements of the installation;

Fig. 2 is a general plan view of the complete apparatus showing the turnover plate in position for application of the molding flask;

Fig. 3 is an enlarged plan view of the supporting and operating elements of the equalizing table;

Fig. 4 is a view of the same in side elevation; and

Fig. 5 is a cross sectional view on line V—V of Fig. 3.

The turnover and flask lowering mechanism is generally indicated at A and is in

operative relation to the jarring machine B, both of which are of well known construction, and generally similar to the apparatus shown in the above mentioned patent.

The jarring machine B is provided with the usual table 2 upon which the flask 3 is supported with the intervening pattern supporting turnover plate 4. These elements, as well as the vibrating mechanism for jarring the table, are of well understood construction and operation, and need not be further described.

The turnover plate 4 is provided at each end with lateral socket projections 5 having tapered sockets for engagement by tapered trunnions 6 of the usual turnover arms 7 by which the plate 4 and flask 3 are swung over upwardly above the withdrawing and equalizing table, as indicated in dotted lines in Fig. 1.

Arms 7 are mounted on rock-shaft 8 extending across in bearings 9 of the main frame of the machine and operatively connected by lever 10 and connecting rod 11 with plunger 12 of cylinder 13. Said cylinder and its parts are also generally similar to that of the said patent, and operate to throw lever 10 and rock-shaft 8 around through one-quarter revolution more or less.

Rotation of the turnover plate 4 and flask 3 is effected by restraining or limiting action of controlling rods 14 pivotally mounted at 15 and connected at 16 with the trunnions 6, so that as the turnover arms swing upwardly and over, the position of the flask is reversed above the equalizing table as shown.

Flask 3 is provided with the usual bottom board and battens 17 against which the contacting elements of the equalizing table engage when elevated.

Equalizing table 18 comprises a middle base plate which is fixedly mounted upon the upper end of plunger 19 of cylinder 20 connected by a conduit 21 with controlling valve C more fully illustrated and described in my companion application Serial Number 366,863, May 29, 1929.

Bed plate or table 18 is provided with downwardly extending guide rods 22 and 22a. Rods 22 are provided with cushioning springs 130

23 and 24 adapted to absorb the shock of impact on either downward or upward movement against the intervening guide abutments 25 and 25a.

5 Table 18, which generally conforms more or less to the face area of the bottom board and battens of the flask, is provided along each side with resiliently mounted contact bars or rails 26 having upper contacting edges 27 for engagement against the under side of the battens or other surface portions of the under side of the reversed flask 3.

One of the objects of the present invention is to so mount the rails 26 that their contacting edges 27 will independently engage against the surface to be supported, and will automatically adjust themselves thereto, one independently of the other, upon coming into contact therewith, whereby to entirely support the flask when fixed in such position, for positive and accurate lowering thereof without danger of harmful variation of the flask and molded sand in withdrawal from the pattern.

25 For such purpose each rail is mounted by portions intermediate of its ends upon resisting cushioning springs 28 seated in casings 29 therefor, mounted on the outer edge portions 30 of table 18. Each bar or rail 26 is provided with enlarged and downwardly open cup-shaped housings 31 telescoping over the members 29 and providing an enclosing bearing for the springs.

As thus constructed, as the equalizing table 35 is brought upwardly into contact with the under side of the inverted flask, and with the slight pressure present at the upward end of the stroke of plunger 19, each rail will automatically accommodate itself to such under side, either in parallelism or with more or less deflection at one side or the other or both, dependent on any corresponding variation in one or the other or both sides of the flask bottom.

45 For the purpose of positively fixing the rails in such adjusted position so as to temporarily hold them in proper contacting relation with the flask, during lowering movement thereof by release of pressure from cylinder 20, I provide the holding mechanism for the rails illustrated in Figs. 2 and 3.

The rails themselves lie inwardly against or in close proximity to the outer side faces of upstanding posts or abutments 32 arranged along each side of the equalizing table 18, against which the rails are to be tightly clamped and held against accidental or other movement during lowering of the table.

55 For such purpose I provide a lever 33 pivotally connected at 34 and 35 with oppositely extending links 36 having integral bolts 38, extending outwardly in opposite directions through the middle portion of each rail, and having terminal adjusting and securing nuts 39. The opposite end of lever 33 is connected

at 40 with the clevis terminal 41 of piston rod 42 of the spring-retracted plunger 43 in cylinder 44. When it is desired to fixedly hold the rails 26 in tight abutting contact with posts 32, pressure is applied to plunger 43 by flexibly connected conduit 45 from any source of pressure, subject to the opening and closing of a suitable controlling valve, not shown, at any convenient location within reach of the operator.

70 When thus tightly clamped, and the flask 3 has been released from the turnover plate by removal of clamps 46, the flask resting evenly and stably on the edges 27 of the rails may be positively and evenly lowered downwardly below the pattern, so that the turnover plate may then be returned to its initial position over the bumper and the pattern removed for substitution by an additional pattern and flask.

75 The lowering of the flask, under control of valve C, is at first comparatively slow and then more rapidly, or with any desired variation in speed under control of the operating valve C, as is more fully described in my 80 companion application mentioned.

85 The construction and operation of the invention will be readily understood and appreciated from the foregoing description and it will be found to be continuously efficient and to avoid the usual objections and trouble incident to improper or variable lowering of the flask, avoiding any even slight variation, and resulting in a perfectly formed mold cavity. The side rails may be of any desired 90 design, dimension, spacing, or otherwise changed or modified to suit conditions of use, and the mechanism itself may be changed or varied by the skilled mechanic, but all such changes are to be understood as within the 95 scope of the following claims.

100 I claim:

1. In a bumping machine, the combination of a flask support, means for raising and turning the flask support, and a flask supporting equalizing table having a pair of independently adjustable vertically cushioned 105 supporting rails.

2. In a bumping machine, the combination of a flask support, means for raising and turning the flask support, and a flask supporting equalizing table having a pair of independently adjustable vertically cushioned supporting rails and means for holding them in adjusted position.

110 3. In a bumping machine, the combination of a flask support and flask thereon, means for raising and turning the flask support and flask to inverted position, and a flask supporting equalizing table having resiliently mounted vertically cushioned bearing elements for contact with the flask, and tightening means therefor.

115 4. In a bumping machine, the combination of a flask support and flask thereon, means 120

for raising and turning the flask support and flask to inverted position, and a flask supporting equalizing table having a pair of independent resiliently mounted vertically cushioned flask bearing rails adapted to make supporting contact with the flask, and means on the table for fixedly holding the rails in supporting position.

5. In a bumping machine, the combination of a flask support and flask thereon, means for raising and turning the flask support and flask to inverted position, and a flask supporting equalizing table having a pair of independent resiliently mounted vertically cushioned flask bearing rails adapted to make supporting contact with the flask, resisting abutments on the table, and means for tightening the rails against said abutments in flask supporting position.

10. 6. In a bumping machine, the combination of a flask support and flask thereon, means for raising and turning the flask support and flask to inverted position, a vertically movable plunger, and a flask supporting equalizing table mounted on the plunger having resiliently mounted vertically cushioned bearing rails for contact with the flask and tightening means therefor.

15. 7. In an equalizing table for supporting and lowering a flask from its pattern, a frame having oppositely located bearing members, resilient supporting means therefor, resisting abutments, and lever mechanism for binding the bearing members against said abutments.

20. 8. In an equalizing table for supporting and lowering a flask from its pattern, a frame having oppositely located bearing members, resilient supporting means therefor, resisting abutments, lever mechanism for binding the bearing members against said abutments, and a fluid actuated plunger for actuating the lever mechanism.

25. 9. In an equalizing table for supporting and lowering a flask from its pattern, a frame having oppositely located bearing rails, resilient supports therefor, resisting abutments for the rails, a lever having link connection with the rails, a cylinder, and a fluid actuated plunger in the cylinder connected with said lever.

30. In testimony whereof I hereunto affix my signature.

ROBERT F. RINGLE.
